INVENTOR:

C. G. Weinreich.
BY
Felix J. Haran,
ATTORNEY.

UNITED STATES PATENT OFFICE.

CHRIST G. WEINREICH, OF ST. LOUIS, MISSOURI.

DEVICE FOR LOCATING SUBMERGED BODIES.

Application filed April 25, 1927. Serial No. 186,337.

This invention relates to a device for locating submerged bodies.

The object of the invention is first, the provision of a vertically movable lamp and reflector carried within a tubular member; second, the provision of means for holding the lamp and reflector at any desired elevation within the tubular member; third, the provision of means for closing the upper 10 openings in the tubular member should water enter the tubular member; fourth, the provision of means for connecting a light and an observation tube to the bottom of the hull of a watercraft having light and 15 sight openings therein; fifth, the provision of means for automatically closing the upper sight openings of the observation tube should the tube be filled with water entering from the lower end thereof; and, sixth, the provision of means for manually closing the 20 light and sight openings in the bottom of the hull of the watercraft.

A further object of the invention is the provision of a device for locating submerged bodies which possesses advantages in points of simplicity and efficiency, and, at the same time proves itself comparatively inexpensive in cost of manufacture.

With the above and other objects in view, 30 the invention consists in the novel features of construction, arrangement and combination of parts hereinafter more fully described and finally pointed out in the claims hereto appended.

35 Referring to the accompanying drawings forming a part of this specification, wherein like characters of reference denote similar parts throughout the several views:

Fig. 1, is a vertical sectional elevation of 40 a device embodying the features of my invention, and, it is shown as fixed, or applied to the hull of a submarine, or other watercraft.

Fig. 2, is a top plan view thereof.

45 Fig. 3, is a side elevation of the device as applied to and depending from a buoyant body.

Referring to the drawings, the reference 50 numeral 1 designates a portion of the bottom of the hull of a boat, ship, or other suitable watercraft, which is provided with a light opening 2 and an adjacent sight opening 3, which openings are open while searching, scientific, or other investigations are being 55 made under water, and which openings are simultaneously closed by means of the ex-

terior closure plate 4 when investigations are not being made. The closure plate 4 is actuated or rotated through the medium of the shaft 5 having a handle 6. The shaft 60 5 is fixed at its lower end to the plate 4 and is supported above the plate 4 in a suitable bearing member 7 forming a part or carried by and within the bottom 1 of the hull.

The bottom 1 of the hull is provided with the adjacent screw threaded recesses 8 and 9 which are concentric with the light and sight openings 2 and 3, respectively, and which provide the rest shoulders 10 and 11, 70 respectively. A light, or lamp tube 13 consisting of one or more suitable cylindrical tube sections 14 which are united by a suitable coupling member 15 when more than one tube section is employed, is seated at its lower end in the recess 8. The lower end of the light tube is provided with a flanged screw threaded gland member 16 and with an interior shoulder flange 17 between which flange and gland member is positioned a suitable flat transparent window 18. The tube 13 is held from upward and lateral displacement by means of a gland member 19 which encircles the tube 13 and also has screw threaded connection with the recess 8 above 85 the flanged gland 10. The upper end of the tube 13 is provided with a closure cap 19' which is provided with a centrally arranged swivel sleeve 20 having an opening 21. The sleeve 20 is provided with a closure plate 22 90 which engages the inner face of the cap for closing an opening 23 in the cap 19' should the window 18 be broken from any cause while the boat is submerged, thus preventing the inrush of water into the interior of 95 the boat from the tube 13. To prevent water from finding its way through the sleeve 20, it is provided with a boss having a conical seat 24 into which can be seated a tapered projection 25 carried by a fixture 26 within 100 the tube 13. A suitable cable 27 is carried upon a reel drum 28, which drum is revolvably mounted in the bearings 29 which are fixed to the closure cap 19. The cable 27 passes from the rotatable reel drum 28 downwardly through the sleeve 20 and has suitable connection with the fixture member 26 for lowering and raising a light within the tube 13. The reel shaft 30 is provided with a ratchet wheel 31 and one of the bearings 29 105 is provided with a dog 32 for engaging the ratchet wheel to hold the light within the

110

tube 13 at any desired elevation therein. The reel shaft 30 is provided with a suitable handle 33 for revolving the reel drum 28. The lamp within the tube 13 consists of 5 a suitably shaped tubular reflector body 34 having an upwardly directed and contracted neck section 35 provided in its upper wall with a square central opening 36 to receive the square portion 37 of a screw threaded 10 shank 38 extending from the socket member 39 which carries a suitable candle powered electric bulb 40. The shank 38 has screw threaded connection with the fixture member 26 for supporting the socket 39 and the 15 reflector 34. The lower end of the reflector is provided with a removable and reversible lens 41 having one curved face to spread the light rays when desired, and with a flat face to direct the light rays to a point if 20 desired. The lens 41 is held between a reflector flange 42 and a removable ring member 43. The wall of the reflector 34 is provided with a plurality of cold air inlet openings 44 and the neck portion thereof is provided with a plurality of circulating warm 25 air outlet openings 45 so as to keep the lamp cool. A short conductor cable connection 46 extends from the socket 39 to a separable connection 47 from which extends additional 30 conductor cable 48 which passes through opening 23. This connection 47 permits of the cable being separated should the window 18 be broken allowing the short end 46 to be dropped into the tube to allow the closure 35 plate 22 to move to close the opening 23.

Arranged in spaced parallel relation with the lamp tube is a sight or observation tube 49 consisting of one or more suitable cylindrical sections 50 which are united by a suitable coupling member 51 when more than one tube section is employed. The tube 49 is seated at its lower end in the recess 9 of the hull bottom 1. The lower end of the observation tube 49 is provided with a 45 flanged screw threaded gland 52 and with an interior shoulder flange 53 between which flange 53 and gland member 52 is positioned a suitable flat transparent window 54. The tube 49 is held from upward and lateral displacement by means of a gland member 55 which encircles the tube and which also has screw threaded connection with the recess 9 above the flanged gland 52. The upper end of the tube 49 is provided with a closure cap 55' which is provided with a pair of openings to receive the lower ends of the sight tubes 56 and 57 which are connected by means of a connecting member 58 which is secured to the cap 55' by means of a suitable 60 fastening device 59. Pivottally connected within the tube 49 below the cap 55' are a pair of closure plates designated 60 and 61 which will automatically raise by the inrushing water pressure for closing the lower ends of 65 the sight tubes 56 and 57 should the window,

54 be broken from any cause while a boat is submerged, thus preventing the water rushing into the observation tube 49 from escaping into the boat through the sight tubes 56 and 57.

In operation:

The operator first turns the shutter or closure plate 4 so as to uncover the lower sight openings 2 and 3 of the tubes 13 and 49. He then lights the lamp 40 and looks downwardly through the observation tube 49 through the upper sight openings 56 and 57 and the lower sight opening 3. Assuming that the light is in the upper end of the light tube 13 and the light rays therefrom do not penetrate the water far enough, the operator lowers the lamp and reflector to the desired elevation within the light tube until the observer can see the article or body to be inspected by observation.

In Figure 3 of the drawings, I have shown the tubes 13 and 49, as strapped together by the connecting members 62 and supported by and depending into the water from a suitable floating body 1'. The tubes 13 and 49 as shown in Fig. 1, do not submerge into the water, but are within the hull, whereas in Fig. 3, the tubes are shown as directly submerged into the water.

I do not wish to be understood as having limited myself to the exact details of construction shown and described, but desire to have it understood that the invention I have shown in the drawings is merely illustrative as it is manifest that various minor changes may be made in the exact construction and particular arrangement of parts without departing from the spirit of my invention, hence I reserve the rights to make any such changes, or modifications as may fairly fall within the scope of the appended claims when fairly construed.

What I claim is:

1. In a device of the class described, in combination with the hull of a watercraft having a light opening and a sight opening therein, a tube supported by the hull in alignment with the light opening therein, a vertically movable reflector within the light tube, a lens carried by the lower end of the reflector, an electric lamp within the reflector, a transparent window removably carried within the lower end of the light tube, cable openings within the upper end of said tube, means for closing said openings, an observation tube supported by the hull in alignment with the sight opening therein, sight openings in the upper end of said tube and means for automatically closing said upper sight openings should the observation tube be accidentally filled with water.

2. In a device of the class described, in combination with the hull of a watercraft having a light opening and a sight opening

therein, means for opening and closing said openings, a screw threaded recess formed in the hull above each opening therein, a tube seated in the recess above said light opening, 5 a gland for holding the tube against displacement, a revoluble member, means to prevent rotation of said member, a cable wound around said member and entering said tube a reflector connected to said cable, 10 a lens carried by said reflector, an electric lamp bulb carried within said reflector, a separable conductor leading to said lamp bulb and passing through the upper end of said tube through an opening therein, means for closing said opening when the cable is 15 separated, an observation tube seated in the recess above said sight opening in the hull, a gland retaining the observation tube against displacement, said tube having sight openings in its upper end and means for 20 closing said openings.

In testimony whereof I have hereunto affixed my signature.

CHRIST G. WEINREICH.
